UNITED STATES PATENT OFFICE.

EWALD HANUS, OF TEGEL, NEAR BERLIN, GERMANY.

BALL-GRINDING MACHINE.

1,207,691.

Specification of Letters Patent.

Patented Dec. 5, 1916.

Application filed October 30, 1916. Serial No. 128,616.

To all whom it may concern:

Be it known that I, EWALD HANUS, engineer, subject of the King of Prussia, residing at Tegel, near Berlin, Germany, have 5 invented certain new and useful Improvements in Ball-Grinding Machines, of which the following is a specification.

The present invention relates to ball-grinding machines, and especially to machines of the type shown and described in 10 by prior Patent, No. 1,124,018, granted January 5, 1915.

In that type of ball-grinding machine, the stationary central plate is provided with 15 a charging recess or hopper which has a width equal to the thickness of the plate and has a gable-shaped bottom, the latter serving to deflect the balls to one or the other of the rotatable plates. Experience has shown, 20 however, that such bottom alone fails to effect an even distribution of the balls, so that they frequently become crowded at the entrance to the grooves at one side of the hopper, and it is to overcome this defect 25 that I have devised the present improved form of hopper.

According to the invention, there is provided above the gable-shaped bottom a device which acts as a regulator and distributor 30 for the balls as they leave the grooves and fall into the hopper, and which also serves as a collector for the surplus balls, so that said balls, instead of falling irregularly to one side of the other, are strewn 35 evenly over the ridge or cope of the bottom.

An embodiment of the invention is illustrated in the accompanying drawing, whereof:

Figure 1 is a side elevation, with parts in 40 section and broken away; Fig. 2 is a vertical section on line 2—2, Fig. 1; Figs. 3 and 4 are details of slight modifications; and Figs. 5 and 6 are details, on a greatly-enlarged scale, of the hopper represented in 45 Figs. 1, 2 and 3.

In the construction illustrated, as in the patented construction, the grooved, stationary, central plate *a* is fitted between the grooved faces of the two rotatable outer 50 plates *f* and *g*, and is mounted above the semi-cylindrical casing *s*. The front portion *s*¹ of this casing partly closes the charging recess or hopper *d* formed in the central plate *a*, as shown; but the gable-shaped deflecting bottom of said hopper, instead of 55 constituting an integral part thereof, con-

sists of a metal plate *u*, bent into inverted V- or gable-shape and supported at opposite ends of its ridge or cope upon front and rear pins *v*, secured respectively, to the casing member *s*¹ and to the hub portion *a*¹ of plate *a*.

The distributor is located in the hopper or recess above the deflector *u*, and, in the form shown in Figs. 1, 2 and 3, comprises a pair 60 of metal plates *o*¹ and *o*², disposed at substantially the same angle to each other as the wings of the said deflector. These plates are supported at their opposite ends upon upper and lower pairs of pins *t* and *t*¹, the 65 pins at the front ends of the plates likewise being fixed to the casing member *s*¹, and those at the rear ends of the plates to the hub *a*¹. The bent outer edges of the plates are hooked over the upper pins *t*, as shown, 70 and their lower or inner edges are spaced apart to provide a discharge passage that is disposed directly over the ridge line of the deflector, so that as the balls fall out of the 75 grooves in the rotatable plates *f* and *g*, on reaching the hopper, they will collect in the distributor and be discharged through said 80 passage evenly upon both wings of the deflector, as represented in Fig. 5. The outer side edges of the distributor plates may be 85 so arranged as to strip from the grooves in the rotatable plates any balls which happen to stick therein from any cause; or, if preferred, separate strippers *w* may be provided, said strippers having their front or 90 outer ends supported in a notch *w*² in the casing member *s*¹, and their inner or rear ends supported on a pin or pins *w*¹ fixed to the hub *a*¹.

In addition to the plates *o*¹ and *o*², the 95 distributor may comprise a rotary agitator, shown in Fig. 3, and in dotted lines in Fig. 5, which embodies a horizontal shaft *y*¹ that projects into the space between said plates and is provided with radial blades *y*, said 100 shaft being driven from any suitable source of power. The agitator acts to keep the balls in motion, as will be apparent, thereby facilitating their passage through the discharge opening and preventing them 10 from becoming packed therein.

In the form depicted in Fig. 4, there is shown a collecting and distributing device embodying a pair of agitators, said agitators comprising a pair of horizontal shafts 11 *x*¹ and *x*², each provided with radial blades *x*, made of leather or other suitable material.

The agitators are driven toward each other, and are disposed above the wings of the bottom plate u , so that as the balls fall out of the grooves, or are removed therefrom by 5 the action of the strippers, they will drop into the spaces or pockets between the blades, and, before reaching the bottom of the hopper, will be whirled around, mixed, and discharged toward opposite sides of the 10 deflector. In this form, as illustrated, the inclined plates are omitted to render the showing of the two agitators clearer; but it is to be understood, that they may be located above said agitators to guide and de- 15 liver the balls thereto.

I claim as my invention:—

1. In a ball-grinding machine, the combination of a pair of rotatable grinding plates arranged in spaced, parallel relation 20 to each other; a stationary grinding plate arranged in the space between the rotatable grinding plates and provided with a charging recess which has a width equal to the thickness of that plate and which has a 25 gable-shaped bottom; and a funnel-shaped distributor located within said charging recess above said bottom, and having a longitudinal discharge opening which directly overlies the ridge line of said bottom.
- 30 2. In a ball-grinding machine, the combination of a pair of rotatable grinding plates arranged in spaced, parallel relation to each other; a stationary grinding plate arranged in the space between the rotatable 35 grinding plates and provided with a charging recess which has a width equal to the thickness of that plate and which has a gable-shaped bottom; and means located within said charging recess to receive the 40 balls from said rotatable grinding plates and to mix them up and distribute them evenly upon opposite sides of said bottom.
3. In a ball-grinding machine, the combination of a pair of rotatable grinding 45 plates arranged in spaced, parallel relation to each other; a stationary grinding plate arranged in the space between the rotatable grinding plates and provided with a charging recess which has a width equal to the 50 thickness of that plate and which has a gable-shaped bottom; a funnel-shaped distributor located within said charging recess above said bottom, and having a longitudinal discharge opening which directly 55 overlies the ridge line of said bottom; and a rotary agitator disposed within said distributor directly above and parallel with said discharge opening.
4. In a ball-grinding machine, the combination of a pair of rotatable grinding 60

plates arranged in spaced, parallel relation to each other; a stationary grinding plate arranged in the space between the rotatable grinding plates and provided with a charging recess which has a width equal to the 65 thickness of that plate and which has a gable-shaped bottom; and a pair of plates disposed within said charging recess above said bottom and inclined toward each other, said plates having their lower longitudinal 70 edges spaced apart to form a longitudinal discharge opening which directly overlies the ridge line of said bottom.

5. In a ball-grinding machine, the combination of a pair of rotatable grinding 75 plates arranged in spaced, parallel relation to each other; a stationary grinding plate arranged in the space between the rotatable grinding plates and provided with a charging recess which has a width equal to the 80 thickness of that plate and which has a gable-shaped bottom; a semi-cylindrical casing surrounding the lower portion of the stationary grinding plate; upper and lower pairs of pins secured to the inner face of the 85 front portion of said casing and to the hub of said stationary grinding plate; and a pair of plates disposed within said charging recess above said bottom and having their outer longitudinal edges hooked over 90 the upper pins and their lower edges resting upon the lower pins in spaced relation to form a discharge opening which directly overlies the ridge line of said bottom; said pin-supported plates being inclined toward 95 each other to direct the balls deposited thereon from said rotatable grinding plates toward said discharge opening.

6. In a ball-grinding machine, the combination of a pair of rotatable grinding 100 plates arranged in spaced, parallel relation to each other and having their inner faces formed with annular grooves; a stationary grinding plate arranged in the space between the rotatable grinding plates and provided with a charging recess which has a width equal to the thickness of that plate 105 and which has a gable-shaped bottom; a semi-cylindrical casing surrounding the lower portion of the stationary grinding plate and extending across the lower portion of said charging recess; and a pair of scrapers extending through said charging recess in position to engage the balls in said grooves and remove them therefrom, said 110 scrapers having their front ends supported upon said casing and their rear ends upon the hub of said stationary grinding plate.

In testimony whereof I affix my signature.
EWALD HANUS.
